UNITED STATES PATENT OFFICE

1,982,275

TRACK BRACKET AND STOP

Axel Wasberg, Chicago, Ill., assignor to Camel Company, Chicago, Ill., a corporation of Illinois

Application January 2, 1932, Serial No. 584,339

13 Claims. (Cl. 20—22)

This invention relates to a door stop for house cars and concerns itself with means for maintaining said stop a constant distance from the door supporting track.

It is common practice in house cars for transporting vehicles to provide a pair of cooperating doors, one of which carries a jamb which is adapted to be anchored to the top and bottom portions of the car. Usually, a stop member is provided for arresting the movement of the jamb when the door containing such jamb is in its closed position. In the past, it has been the usual practice to attach this stop member to the top of the threshold plate, the top of the floor, or directly to the side sill according to the construction of the car. The supporting track for the door customarily is attached to brackets extending from the side sill. A certain amount of clearance between the movable jamb and the stop therefor is always necessary and this clearance is frequently destroyed through a swelling or shrinking of the floor or the positioning of the track above or below the gage line. It will also be appreciated that this clearance may become varied through variations in the thickness of the track or variations between the rollers on the door and their supporting axle. Due to the various variations in construction, it is extremely difficult to maintain a proper clearance between the movable door jamb and the stop therefor.

It is an object of this invention to provide a structure having a constant clearance between the movable door jamb and the stop therefor. The manner in which this object is accomplished resides in a fixed relation between the door stop and the supporting track. More specifically, the invention consists in a door stop member that is rigidly attached to the car supporting track or forms a portion of the supporting structure for such track.

The invention comprises the novel structure and combination of parts hereinafter described and more particularly pointed out and defined in the appended claims.

In the accompanying drawings which illustrate a preferred form of this invention and in which similar reference numerals refer to similar features in the different views:

Figure 1 is a fragmentary side elevational view of a house car equipped with a pair of doors embodying a stop mechanism involving this invention.

Figure 2 is an enlarged broken sectional view taken upon the line II—II of Figure 1 looking in the direction of the arrow.

Figure 3 is a fragmentary vertical sectional view taken upon the line III—III of Figure 2 looking in the direction of the arrows.

Figure 4 is a horizontal sectional view taken upon an enlarged scale upon the line IV—IV of Figure 2 looking in the direction of the arrow.

Figure 5 is an enlarged top plan view of the stop member for the movable door jamb.

Figure 6 is an end elevational view of said stop member.

Figure 7 is a front elevational view of the stop member.

In connection with this invention, there is shown a car door 1 which may be of any desired construction. This door 1 carries a jamb 2 at its forward edge and this jamb is provided with a toe portion 3 which is adapted to be arrested by the forward wall 4 of a stop member generally denoted by the reference numeral 5.

This stop member has a pair of side walls 6 which slope outwardly at their forward ends as shown more clearly in Figure 5. One edge wall of the stop member embodies an upwardly sloping portion 7 terminating in a depending flange 8 which is spaced from the wall 4 to provide a socket for the toe 3 shown in Figure 3. The stop member is provided with a flange 9 upon each end for attachment to the side sill 10 of the car and it is further provided with a U-shaped off-set 11 which engages the door supporting track 12 and is attached thereto. It will of course be understood that suitable provision must be made in the floor of the car for accommodating the stop member 5, as shown in Figure 3.

While the door 1 may be supported in various ways, it has been shown as supported upon a pair of bearing balls 13 which are confined in a retainer 14 which may be eccentrically pivoted to suitable castings upon the ends of the door as is well known in the art for transverse rocking movement for elevating and lowering the door. When the door is in its elevated position, and traveling upon the rollers, the toe portion 3 will ride over the flange 7 of the stop member until it is arrested by the wall 4 and when the door is lowered, the toe portion will engage the socket formed between the wall portion 4 and the depending flange 8 and become locked in closed position, as is apparent from an inspection of Figure 3.

The stop bracket 5 may also be provided with

a stop rib 15 for arresting the cooperating door 16 in the event that two doors are used.

Due to the particular construction of the stop member 5, it is desirable to mount the car door 1 upon a separate track section which may be removed together with the bracket 5 when it is desired to remove the door 1 for repairs. For this purpose, the supporting track 12 for the door may be made in two sections with the line of division 10 at the meeting edges of the door as shown in Figure 4. This will render it possible to remove the track section that supports the door 1 when it is desired to remove said door for repairs.

It will be appreciated that, according to this invention, a constant clearance will be maintained between the lower stop member 5 and the lower end of the post or jamb 2 for proper functioning of the parts. It will be readily apparent that the door supporting track and the side sill 20 and the stop member for the door occupy a fixed relation that will not be disturbed by any variations arising from the weather or from the materials or construction or from the construction of the parts.

25 I am aware that many changes may be made and numerous details of construction may be varied through a wide range without departing from the principles of this invention, and I therefore do not purpose limiting the patent granted hereon otherwise than necessitated by the prior art.

I claim as my invention:

1. In a house car having a track, a door mounted upon said track, a bracket secured to said track and having a stop lug located inside of the plane of the door, and a post on said door adapted for engaging said stop lug.

2. In a house car having a track, a door mounted upon said track for elevating and lowering movements, a post upon the front end of said door, a stop member secured to said track and having an abutment in the path of said door, and a socket adjacent said abutment adapted for receiving the lower end of said post when said door is lowered.

3. In a house car having a side sill and a track, a bracket between said side sill and track, means for attaching said bracket to said side sill and track, a door mounted upon said track, a post upon said door, said bracket having an upwardly extending portion inside of said track forming a stop for said post.

4. In a house car having a track, a door mounted upon said track, a post upon said door, a bracket secured to the inner side of said track and extending upwardly inside of the plane of the door and forming a stop for said post, said bracket having side walls between which the foot of the post is adapted to pass.

5. In a house car, a track, a door supported upon said track, a post carried by said door, a bracket secured to said track and extending upwardly inside of the plane of the door and having a guideway for receiving the lower end of

said post and a stop lug at one end of said guideway for arresting said post.

6. In a house car, a track, a door supported upon said track, a post carried by said door, a bracket secured to said track and extending upwardly inside the plane of the door and having a recess in the path of said post for receiving and arresting said post. 80

7. In a house car having a side sill and a track, a bracket between said side sill and track, means for attaching said bracket to said side sill and track, a door mounted upon said track, a post upon said door, said bracket having an upwardly extending portion located between the planes of said sill and track and extending into the path of said post for the purpose set forth. 85

8. In a house car having a side sill and track, a bracket between said side sill and track and secured to said side sill and attached to said track for supporting the same, a pair of cooperating doors upon said track, said bracket having stops extending into the paths of said doors for arresting the same in closed position, one of said stops extending upwardly inside the plane of said doors. 95

9. In a house car having a side sill, a track, means for supporting said track upon said side sill including a bracket between said side sill and track and attached to said side sill and track and extending upwardly, a pair of cooperating doors mounted upon said track, one of said doors having a post and said bracket having stop lugs for engagement by said post and the cooperating door. 100

10. In a house car having a side sill, a track supporting bracket secured to said side sill, a track secured to the outer margin of said bracket, said bracket having an upwardly extending stop lug, and a door mounted upon said track and having a post adapted for engaging said stop lug, said lug being located inside of the plane of the door. 110

11. In a house car having a side sill, a combined track supporting bracket and stop secured to said side sill, a track secured to said bracket, a door mounted upon said track and having means for engaging the stop on said bracket, said stop extending upwardly between said sill and track. 120

12. In a house car having a side sill and track in spaced relation, a bracket therebetween, means for attaching said bracket to said sill and track, a pair of cooperating doors mounted upon said track, one of said doors carrying a post, said bracket having a lug forming a stop for one door and a lug at a higher elevation for engagement by the post of the other door. 125

13. In a house car having a side sill and a track in spaced relation, a bracket therebetween and secured to each, a pair of cooperating doors mounted upon said track, said bracket having stop lugs at different elevations for arresting said doors in their closed positions. 135

AXEL WASBERG.
